COLLAPSIBLE GARMENT FORM Benjamin Wexler and Marvin C. Wexler,
Philadelphia, Pa.

Application August 30, 1956, Serial No. 607,154

14 Claims. (Cl. 223—68)

This invention relates generally to garment forms and more particularly to improvements in collapsible garment forms.

A principal object of the present invention is to provide a garment form with a frame which may be collapsed without any section thereof folding over another, whereby the bulk of the collapsed frame is reduced to a minimum.

Another principal object of the present invention is to provide such a garment form the size of which may be conveniently varied between predetermined limits at the hips, waist and bust lines or selectively at any one or more of the lines aforesaid.

And still another principal object of the present invention is to provide such a garment form with an outer covering which may be removed from the frame for adjustment of the latter to a selected size, and which self-adjusts to the selected frame size when replaced.

Other objects and advantages of the present invention will appear more fully hereinafter, it being understood that the invention consists substantially in the combination, construction, location and relative arrangement of parts, all as described in the accompanying drawings and as finally pointed out in the appended claims.

In the accompanying drawings:

Figure 1 is a perspective view of a garment form constructed in accordance with and embodying the principles of the present invention;

Figure 2 is a view looking at the inner side of the front panel of the frame covering;

Figure 3 is a view looking at the inner side of the back panel of the frame covering;

Figure 4 is an enlarged section taken on line 4—4 of Figure 1;

Figure 5 is a side view of a neck forming part of the frame covering;

Figure 6 is a perspective view of a frame member;

Figure 7 is a front view of the frame in expanded conditions;

Figure 8 is a plan view of the frame in expanded condition;

Figure 9 is a partially exploded perspective view of a base portion of the frame;

Figure 10 is a perspective view showing linkage for expanding and collapsing the frame;

Figure 11 is an enlarged section taken generally on line 11—11 of Figure 7;

Figure 12 is an enlarged section taken on line 12—12 of Figure 7;

Figure 13 is a side view of the frame in expanded condition;

Figure 14 is the same as Figure 13, but the frame is shown in collapsed condition;

Figure 15 is an enlarged section taken on line 15—15 of Figure 7;

Figure 16 is a section taken on line 16—16 of Figure 15;

2

Figure 17 is the same as Figure 16, but the frame is in collapsed condition; and

Figure 18 is a section taken on line 18—18 of Figure 17.

5 Referring to the drawings, and particularly to Figure 1, the garment form constructed in accordance with and embodying the present invention comprises a covering 10 that closely resembles in shape the trunk of the human body and which is fitted over an open frame structure 11 mounted upon a stand 12.

Referring particularly to Figures 1 through 4, the covering 10 includes a front panel 13, a back panel 14 and zipper means for detachably securing these panels together. The front panel is provided with an outer felt cloth 15 and a set of three longitudinally extending fibre board stays, respectively designated 16, 17 and 18, that are adhesively secured to the inner face of the felt cloth 15 in close laterally spaced relation to one another. The stay 16 underlies the central one-third area and the stays 20 17 and 18 respectively underlie the opposite side one-third areas of the felt cloth 15. The back panel is provided with an outer felt cloth 19 and a set of three longitudinally extending fibre board stays, respectively designated 20, 21 and 22, that are adhesively secured to the inner face of the felt cloth 19 in close laterally spaced relation to one another. The stay 20 underlies the central one-third area and the stays 21 and 22 respectively underlie the opposite side one-third areas of the felt cloth 19.

30 Each side of the covering 10 is provided with the zipper means aforesaid, which extends along the meeting edges of the panels 13 and 14, from the top to the bottom of the panels. This zipper means includes longitudinally extending parallel strips of cloth 23—23 that are stitched along their remote longitudinally extending edges, as at 24—24, respectively to the outer cloth 15 of the front panel 13 and outer cloth 19 of the back panel 14, and along their proximate longitudinally extending edges, as at 25—25, respectively to a pair of zipper tapes 26—26. 40 The latter conventionally mount interlocked zipper elements 27 that are conventionally operated by a suitable slide 28. It will be understood that the strips of cloth 23—23 are elastic in the direction of their width, in consequence of which the meeting edges of the panels 13 and 14 can be separated as desired, within a limit determined by the elastic capacity of the strips aforesaid.

Referring particularly to Figures 1 and 5, a sheet material neck piece 29 is projected upwardly through an opening 30 formed in the top of the covering 10, the base portion of the neck piece being disposed in underlying relation to the marginal portion of the covering 10 that defines the opening 30.

55 A main section of the open frame structure 11 essentially comprises a pair of laterally spaced upright members 31—31 that extend from the shoulder to the hip line of the frame, a cross tie member 32 that interconnects the lower end portions of the upright members 31—31, a second cross tie member 33 that is vertically spaced 60 above the member 32 and which arches upwardly beyond the shoulder line, and a pair of narrow shoulder plates 34—34 each of which interconnects the upper end of the associated upright member 31 with the opposed portion of the cross tie member 33.

65 Carried by the main frame section is an auxiliary section having a pair of laterally spaced parallel arms 35—35 the rear end portions of which are disposed between and respectively connected to opposed upright portions of the cross tie member 33 by a pair of coaxially related pivots 36—36, and the fore end portions of which mount a chest plate 37 that extends across the front of the main

frame section and which is swingable on the arms 35-35 about the horizontally extending axis of the pivots 36-36.

A second auxiliary section carried by the main frame section has a pair of laterally spaced parallel arms 38-38 and the fore end portions of which are disposed between and respectively connected to opposed upright portions of the cross tie member 33 by a pair of coaxially related pivots 39-39, and the rear end portions of which mount a back plate 40 that extends across the rear of the main frame section and which is swingable on the arms 38-38 about the horizontally extending axis of the pivots 39-39. In the expanded condition of the frame, the shoulder plates 34-34, chest plate 37 and back plate 40 conjointly outline the shoulder, upper chest and upper back area of the human form.

A third auxiliary section carried by the main frame section is provided with a pair of coaxially related axially spaced pivot rods 41-41 proximate end portions of which are journaled respectively in a U-shaped bracket 42 that extends forwardly from the cross tie member 33, and the remote end portions of which are journaled respectively in a pair of elements 43-43 that extend forwardly from the upright members 31-31. The rods 41-41 are axially fixed relative to one another, as by suitable elements designated 43a.

Associated with the pivot rods 41-41 is a flexible band 44 that is suitably shaped to outline the bust of the human body, as shown. For mounting the band 44 upon the rods 41-41, the opposite end portions of the band are each provided with a series of three rectangular apertures 45, and the remote end portions of the pivot rods, designated 46-46, are each made rectangular in shape, in consequence of which the band 44 is removably secured to the remote end portions 46-46 of the pivot rods 41-41 with the latter respectively projecting in opposite directions outwardly freely through a selected pair of the apertures 45-45.

Fourth and fifth auxiliary sections carried by the main frame section are provided respectively with pivot rods 47 and 48. Opposite end portions of the rod 47 are journaled respectively in corresponding fore end portions of a pair of elements 49-49, while opposite end portions of the rod 48 are journaled respectively in corresponding rear end portions of the elements 49-49. These rods 47 and 48 are axially fixed relative to one another, as by elements 43a. The elements 49-49 are secured respectively to opposed portions of the upright members 31-31, whereby the rods 47 and 48 are disposed horizontally in parallel spaced relation. The opposite end terminal portions of the rods 47 and 48 are rectangular in transverse cross section, the portions aforesaid being designated respectively 50-50 and 51-51.

Associated with the pivot rods 47 and 48 respectively are a pair of flexible bands 52 and 53. The opposite end portions of the band 52 are provided with rectangular apertures 54, and the opposite end portions of the band 53 are provided with rectangular apertures 55. These bands, suitably shaped to conjointly outline the waist of the human body, as shown, are mounted upon their pivot rods in a manner similar to that in which the bust outlining band 44 is mounted upon the pivot rods 41-41.

Sixth and seventh auxiliary sections carried by the main frame section are generally the same as the overlying waist outlining auxiliary sections in construction and mounting. The pivot rods, respectively designated 56 and 57, are carried by a pair of elements 58-58, the opposite end terminal portions of the rods 56 and 57 being respectively designated 59-59 and 60-60. The flexible bands associated with the pivot rods 56 and 57, suitably shaped to conjointly outline the hips of the human body, are respectively designated 61 and 62, the apertures in the opposite end portions of the band 61 being designated 63 and the apertures in the opposite end portions of the band 62 being designated 64.

The main frame section includes a pair of upright

brackets 65-65 that are disposed between opposed upright portions of the cross tie member 33. The lower end portions of these brackets are secured respectively to and the upper end portions are disposed respectively in laterally spaced relation to the upright portions aforesaid of the member 33. The brackets 65-65 carry a generally U-shaped plate member that has laterally spaced legs 66-66 and a leg connecting portion 67. These legs 66-66 are pivotally connected by a pair of coaxially related pivot elements 68-68 respectively to the upper end portions of the brackets 65-65. Corresponding portions of the legs 66-66 respectively mount pivot elements 69-69 that extend laterally outwardly therefrom in opposite directions and project freely respectively through elongated openings 70-70 which are formed in the arms 38-38 mounting the upper back plate 40. Depending from the U-shaped plate aforesaid are a pair of links 71-71 the upper end portions of which are connected by coaxially related pivot elements 72-72 respectively to other corresponding portions of the legs 66-66 and the lower end portions of which are connected to laterally offset proximate end portions 73-73 of the pivot rods 41-41 of the chest outlining auxiliary frame section.

Depending respectively from the arms 38-38 that mount the upper back plate 40 are a pair of links 74-74, the upper end portions of which links are connected respectively to the arms 38-38 by a pair of coaxially related pivot elements 75-75. The lower end portions of these links are connected respectively to corresponding portions of a pair of links 76-76 by a pair of coaxially related pivot elements 77-77. These latter links are connected respectively to the brackets 65-65 by a pair of coaxially related pivot elements 78-78 and respectively mount a pair of pivot elements 79-79 that extend laterally outwardly therefrom in opposite directions and project freely respectively through elongated openings 80-80 which are formed in the arms 35-35 mounting the chest plate 37. It will be observed that the U-shaped plate member aforesaid is rockable about the horizontally extending axis of the pivot elements 68-68, which rocking movement is translated into swinging movement of the chest, upper back and bust outlining auxiliary frame sections respectively about the horizontally extending axes of the pivot elements 36-36 and 39-39 and the pivot rods 41-41.

Located centrally in the open frame structure 11 is a rigid rod member 81 an upper end portion of which mounts a set of laterally extending elements 82. A pin 83 that interconnects corresponding portions of the legs 66-66 of the rockable U-shaped plate member extends horizontally freely between these elements 82. The member 81 extends downwardly from the rockable plate member freely between the pivot rods 47 and 48 at the waist line and 56 and 57 at the hip line, being connected to each of the waist and hip outlining auxiliary frame sections through the medium of a pin 84 that extends laterally therefrom and projects freely through an elongated slot 85 which is formed in a link 85 extending laterally from an intermediate portion of the associated pivot rod.

Depending from the rockable plate member is a coil tension spring 87 the upper end portion of which is connected to the leg connecting portion 67 of the U-shaped plate member by an element 88. The lower end portion 65 of this spring is connected to the upright member 81 by an element 89, in consequence of which the rockable U-shaped plate member is constantly biased about the axis of the pivot elements 68-68 in clockwise direction (as viewed in Figure 15), while the rod 81 is constantly biased upwardly. Thus the several auxiliary frame sections are urged to swing in frame expanding direction.

Extending across the front and rear of the crown portion of the arched cross tie member 33 are a pair of plate members 90 and 91 that are suitably flanged over and secured to the member 33. The upper end portion of

the rod member 81 extends freely upwardly between these plates, and the lower edge of the plate 90 is provided with a pair of rod guiding elements 92-92.

Carried by the plate member 90 is a vertically extending leaf spring 93 the upper end portion of which is anchored by means of a rivet 94. The lower end portion of this leaf spring mounts a button 95 that projects freely through an aperture 96 which is formed in the plate 91 and is rearwardly biased against an element 97 that is mounted upon the rod member 81.

Pivottally secured to the plate 91, as at 98, is an operating lever 99 that is laterally offset intermediate its opposite ends, and which extends freely through an arcuate opening 100 formed in the plate 91. This lever is biased in clockwise direction (as viewed in Figure 16) by a tension coil spring 101, and the portion thereof between the plates 90 and 91 is provided with a laterally extending element 102 that has a cam face 103 which engages with the element 97 mounted on the rod member 81.

The stand 12 comprises an upright rod member 104 that is surmounted by a U-shaped member which has a pair of legs 105-105 and a leg connecting portion 106. The upright members 31-31 of the main frame section are channel shaped in transverse cross section and are slidably removably fitted over the legs 105-105 aforesaid. A hook 108 is provided at the top of the open frame structure 11 for use in lieu of the stand 12.

When it is desired to collapse the garment form, the lever 99 is depressed (against the force of the tension spring 101) from the full line to the dotted line position thereof shown in Figure 17, whereupon the rod member 81 is cammed downwardly (against the force of the tension spring 87). To facilitate operation of the lever 99, a suitable finger piece 109 is provided. As the rod member 81 moves downwardly, the auxiliary frame sections at the waist and hip lines fold upwardly against the main frame section and the auxiliary frame sections above the waist line fold downwardly against the main frame section. It will be observed that the chest and bust outlining auxiliary frame sections swing in the same direction, downwardly, while the bust and underlying waist outlining auxiliary frame sections swing in opposite directions, the former downwardly and the latter upwardly. During the collapsing operation, the latter two auxiliary sections swing inwardly close to the main frame section without either interfering in any way with the swinging movement of the other because the opposed portions thereof are complementally arranged to avoid overlapping.

As the rod member 81 reaches the limit of its downward movement, the leaf spring 93 is released and shifts from its position shown in Figure 15 to that shown in Figure 18, in which latter position the lower terminal portion of this leaf spring engages the uppermost surface of the element 97. It will be apparent that the spring 93 is automatically operative to secure the rod member 81 against moving upwardly under the influence of the coil spring 87. After the garment form has collapsed and the lever 99 released, the latter immediately returns to its initial position under the influence of the coil spring 101.

In the event that it is desired to increase or decrease the size of the form, the covering 10 is first removed. This is effected by operating the slides 28-28 to separate the interlocked elements 27 and to thereby separate the front and back panels of the covering 10. After removing the latter, the several flexible bands 44, 52, 53, 61 and 62, or selected ones thereof, are detached from their pivot rods by suitably spreading and manipulating the opposite end portions thereof. Then the several bands aforesaid are remounted with the opposite end portions of their pivot rods engaging desired different apertures. Now the front and back covering panels are replaced and zippered together, automatically self-adjusting to

the new size of the form through the contraction or expansion of the several elastic strips 23. It will be understood that the size of the form may be changed while the frame structure thereof is in collapsed condition, as well as while it is in expanded condition. In addition, the form may be expanded and collapsed without any necessity for removing the covering 10.

It will be understood, of course, that the present invention is susceptible of various changes and modifications which may be made from time to time without departing from the general principles or real spirit thereof, and it is accordingly intended to claim the same broadly, as well as specifically, as indicated in the appended claims.

What is claimed as new and useful is:

1. In a collapsible garment form, a frame comprising an upright main section extending from one side to the opposite side of the form, a plurality of auxiliary sections carried by said main section, and swingable between folded and expanded positions, said auxiliary sections being disposed compactly against said main section when in the former of said positions, and being operative conjointly with said main section to outline the trunk of the human body when in the latter of said positions, certain of said auxiliary sections located in front 20 of the main section respectively in the chest region and at the bust line of the form being mounted for swinging movement downwardly and rearwardly and certain others of said auxiliary sections located in front of the main section respectively at the waist and hip lines of the form being mounted for swinging movement upwardly and rearwardly, said auxiliary sections at the bust and hip lines being adopted for fully executing the swinging movement aforesaid without folding over one another, an elongated member carried by said main section and mounted for axial shifting movement relative thereto, said shiftable member being operatively connected to said auxiliary sections and being operable to simultaneously swing the same between said folded and expanded positions, and spring means associated with said shiftable member and operative to urge the same into such position relative to said main section as to yieldably maintain said auxiliary sections in fully expanded condition.
2. A frame for a collapsible garment form as defined in claim 1 wherein the auxiliary sections at the bust and hip lines are vertically spaced from one another an effective distance greater than the sum of the effective depths of the auxiliary sections aforesaid.
3. A frame for a collapsible garment form as defined in claim 1 wherein the fore edges of the auxiliary sections at the bust and waist lines are respectively concave and convex in form, whereby the fore portion of the auxiliary section at the waist line is freely accommodated by the fore portion of the auxiliary section at the bust line in the collapsed condition of the frame.
4. In a collapsible garment form, a frame comprising an upright main section extending from one side to the opposite side of the form, a plurality of auxiliary sections carried by said main section and swingable about horizontal parallel axes between folded and expanded positions including in front of said main section auxiliary sections respectively located in the chest region and at the bust, waist and hip lines, and to the rear of said main section auxiliary sections respectively located in the upper back region and at the waist and hip lines, and means for collapsing and expanding said frame including a member mounted in the neck region of said frame for rocking movement about an axis parallel to the pivotal axes of said auxiliary sections, said auxiliary sections located in the chest and upper back regions and at the bust line being operatively connected to said rockable member, an elongated member carried by said main section and mounted for axial shifting movement relative thereto, said shiftable member being operatively connected to said rockable member and to the auxiliary

sections located at the waist and hip lines and being operable to simultaneously swing the several auxiliary sections between folded and expanded positions, and spring means associated with said shiftable member and operative to urge the same into such position relative to said main section is to yieldably maintain said auxiliary sections in fully expanded condition.

5. A frame for a collapsible garment form as defined in claim 4 wherein the spring means is a coil tension spring located to the rear of the main frame section and depending from the rockable member, and the opposite end portions of said spring are connected respectively to the rockable and axially shiftable members.

6. A frame for a collapsible garment form as defined in claim 4 wherein the rockable member is U-shaped and disposed between corresponding opposite side portions of said main frame section with the legs thereof straddling and the leg connecting portion located to the rear of the axially shiftable member, and corresponding leg portions of said U-shaped member are pivotally connected respectively to the portions aforesaid of said main frame section.

7. A frame for a collapsible garment form as defined in claim 4 wherein fixedly associated with the auxiliary section at the bust line is an element that extends radially from the pivotal axis thereof, and linkage connected to the rockable member at a point radially spaced from the pivotal axis of the rockable member extends to said element and is pivotally connected to the free end portion of the latter, whereby rocking movement of said rockable member is translated into swinging movement of said auxiliary section.

8. In a collapsible garment form, a frame comprising an upright main section extending from one side to the opposite side of the form, a plurality of auxiliary sections carried by said main section, and swingable between folded and expanded positions, said auxiliary sections being disposed compactly against said main section when in the former of said positions, and being operative conjointly with said main section to outline the trunk of the human body when in the latter of said positions, certain of said auxiliary sections being mountable in a plurality of positions so as to selectively vary the size of the frame at the bust, waist and hip lines, and spring means associated with said shiftable member and operative to urge the same into such position relative to said main section as to yieldably maintain said auxiliary sections in fully expanded condition, and an outer covering removably fitted over said frame and self adjusting to the size thereof.

9. In a garment form as defined in claim 8 wherein the covering for the frame comprises front and back panels conjointly outlining the trunk of the human body and detachably secured together on each side of the form by means extending along the meeting edges of the panels aforesaid and yieldable in a direction normal to said meeting edges.

10. In a garment form as defined in claim 8 wherein the covering for the frame comprises front and back panels conjointly outlining the trunk of the human body and detachably secured together on each side of the form by zipper means extending along the meeting edges of the panels aforesaid including a pair of zipper tapes secured respectively to said panels, by means elastic for yielding in a direction normal to the zipper opening.

11. In a garment form as defined in claim 8 wherein the covering for the frame comprises front and back panels conjointly outlining the trunk of the human body

and detachably secured together on each side of the form by means extending along the meeting edges of the panels aforesaid and yieldable in a direction normal to said meeting edges, and each of said panels comprises an outer pliable cloth and a plurality of longitudinally extending rigid stays secured to the inner face of the cloth aforesaid in side by side relation.

12. In a garment form as defined in claim 8 wherein the covering for the frame comprises front and back panels conjointly outlining the trunk of the human body and detachably secured together on each side of the form by means extending along the meeting edges of the panels aforesaid and yieldable in a direction normal to said meeting edges, and an annular neck forming piece removably embraces the upper end of the frame, the base of said neck piece being fitted into an opening therefore focused in said frame covering.

13. In a collapsible garment form, a frame comprising an upright main section extending from one side to the opposite side of the form, a plurality of auxiliary sections carried by said main section, and swingable between folded and expanded positions, said auxiliary sections being disposed compactly against said main section when in the former of said positions, and being operative conjointly with said main section to outline the trunk of the human body when in the latter of said positions, certain of said auxiliary sections being mountable in a plurality of positions so as to selectively vary the size of the frame at the bust, waist and hip lines, each of said last mentioned auxiliary sections comprising an outer peripherally extending flexible band having a series of perforations formed in its opposite end portions, spring-pressed means operative to yieldably maintain said auxiliary sections in fully expanded condition, and means for removably mounting said band including a pair of coaxially related pivot elements extending horizontally outwardly in opposite directions freely through selected corresponding ones of said apertures.

14. In a collapsible garment form, a frame comprising an upright main section extending from one side to the opposite side of the form, a plurality of auxiliary sections carried by said main section, and swingable between folded and expanded positions, said auxiliary sections being disposed compactly against said main section when in the former of said positions, and being operative conjointly with said main sections to outline the trunk of the human body when in the latter of said positions, certain of said auxiliary sections being mountable in a plurality of positions so as to selectively vary the size of the frame at the bust, waist and hip lines, each of said last mentioned auxiliary sections comprising an outer peripherally extending flexible band having a series of perforations formed in its opposite end portions, spring-pressed means operative to yieldably maintain said auxiliary sections in fully expanded condition, and means for removably mounting said band including a pair of coaxially related pivot elements extending horizontally outwardly in opposite directions respectively beyond the opposite sides of said main section freely through selected corresponding ones of said apertures, said elements being polygonal in transverse cross section and said apertures being correspondingly shaped.
